SEWING MACHINE

Norman V. Christensen, Chicago, George Sauer, Berwyn, and Ned Wallenberg, Chicago, Ill., assignors to Union Special Machine Company, Chicago, Ill., a corporation of Illinois

Application March 11, 1941, Serial No. 382,692

25 Claims. (Cl. 112—256)

This invention relates to sewing machines, and amongst its objects are the attainment in a machine, of greater compactness; to make possible reduction in the number and in the weight of the parts required in the drive or actuating mechanism relied upon for impartation of the necessary movements to the stitch-forming and feeding instrumentalities of the machine (as well as to trimming devices if present); to eliminate as far as possible the need for reciprocating parts particularly in the drive or actuating mechanism; and to enable, for the purpose of self-lubrication, enclosing of the drive or actuating mechanism in a housing of relatively small dimensions, with allocation however of the stitch-forming and feeding instrumentalities (and trimming instrumentalities) externally of such housing, and with provision for the transmission of motion to said instrumentalities from the actuating mechanism to the exclusion of oil leakage from the housing.

In connection with a sewing machine having the above attributes, it is a further aim of our invention to secure the desirable advantages inherent to the use of a straight needle bar which is confined solely to endwise reciprocation.

Other objects and attendant advantages will appear from the following detailed description of the attached drawings, wherein

Fig. 1 shows our improved sewing machine in plan with its top cover removed.

Fig. 2 shows the front elevation of the machine with its top cover removed.

Fig. 3 is a fragmentary view of the machine in front elevation with the top cover in place.

Fig. 4 shows the machine in front elevation with a broken out portion in section taken as approximately indicated by the angled arrows IV—IV in Figs. 6 and 10.

Fig. 5 is a fragmentary view showing the left-hand side elevation of the machine with the top cover in place.

Fig. 6 shows the left-hand side elevation of the machine with a broken out part in section taken as indicated by the angled arrows VI—VI in Figs. 2 and 4, and with the top cover omitted.

Fig. 7 shows the right-hand side elevation of the machine with portions broken out and with portions in section to better illustrate important structural details and to expose certain parts at the interior.

Fig. 8 is a view in plan section taken as indicated by the angled arrows VIII—VIII in Fig. 2, and with portions broken away to expose underlying parts.

Fig. 9 is a transverse section of the machine

taken as approximately indicated by the angled arrows IX—IX in Figs. 1 and 8.

Fig. 10 is a longitudinal section taken as approximately indicated by the angled arrows X—X in Figs. 2, 8 and 9.

Figs. 11—16 are detail views showing successive positions of the needle and the loopers of the machine in the performance of a stitch forming cycle.

- 10 As herein illustrated our improved sewing machine has a box-like base 1 of generally rectangular configuration with integral front, rear and side walls 2, 3, 4 and 5 and bottom 6, in which base a supply of lubricating oil is normally maintained at the level L. Bridging the front and rear walls 2 and 3 of the base 1 intermediate the side walls 4 and 5, is a relatively narrow horizontally-longitudinally-disposed plate-like web 7, see Figs. 1, 2 and 8, which partly closes the base 15 at the top and which constitutes the mid-section 20 at the top which constitutes the mid-section of the work support of the machine. As shown in Figs. 6 and 8, the web 7 is extended as at 7a beyond the front wall 2 of the base 1, and has downwardly-recessed margins 8 along its parallel 25 longitudinal side edges. The base 1 is otherwise closed by horizontal plates 9 and 10, which are positioned to opposite sides of the web 7 and complete the work support. As shown in Figs. 1 and 2, the plates 9 and 10 are flush with the 30 top of the web 7, and are upwardly recessed marginally along their inner edges as at 11 to overlap the downwardly-recessed margins 8 of said web. Screws 12 and 13 respectively engaging downwardly into web 7 and the walls of the base 35 1 serve to removably secure the plates 9 and 10 in place with interposition of sealing gaskets at 14 and 15. From Fig. 1 it is to be noted that the plate 9 at its front end, extends somewhat beyond the web 7 while the plate 10 is coextensive in length with said web. Set into a cut-out in the inner edge of the plate 9 is a throat plate 16 of semi-circular configuration which will be again referred to later.
- 40 The stitch forming mechanism of the machine 45 includes a needle bar 18 which is inclined somewhat to the vertical forwardly in the direction of feeding which is indicated by the arrows in Figs. 1 and 6. As shown in Figs. 1 and 4, the needle bar 18 is disposed in a vertical plane well to the right of the line A—A of feeding (Fig. 1), and passes downward through the mid-section 7 of the work support into a hollow offset or compartment 19 at the front of the base 1, said compartment being set apart from the main compartment or hollow 20 of the base by the front wall 50 55

2 of the latter (Fig. 6) and by a partition 21 (Figs. 4 and 6). From Fig. 6 it will be further observed that the needle bar 18 is confined to endwise reciprocation in oil-tight bushings 22, 23, respectively, set into aligned bores in the web 7 and in the bottom 6 of the base, the lower bushing being secured against displacement by a set screw 25 and closed at its lower end by a screw plug 26. Rotation of the needle bar 18 is prevented through engagement of the lateral projection 27 on a collar 28 secured to said bar, in a vertical slot between two guide plates 29 affixed to the wall 2 within the hollow of the offset 19 of the base 1, see Figs. 4 and 6. Adjustably secured to the top end of the needle bar 18 by a pair of set screws 30, is a laterally-extending arm 31, which, in its end supports, with capacity for endwise and rotative adjustment in the plane A—A (Fig. 1) of stitching and feeding and in parallel relation to said bar, a sewing needle 32.

The stitch-forming mechanism of the illustrated machine further includes a primary or under looper 35 which is external to the base 1 and which cooperates with the needle 32 beneath the throat plate 16; and a secondary or overedge looper 36 which is also external to the base 1, see Figs. 2, 4, 7 and 10. As shown, the loopers 35 and 36 are arranged to operate crosswise of the direction of feeding. The under looper 35, see Figs. 4 and 10, is affixed to the outer end of a short horizontal oscillated shaft 37 which extends, with an oil-tight fit, into the interior of the base 1, through a bearing boss 38 (Fig. 10) on the front wall 2 of said base. At an intermediate point, the overedge looper 36 has a pivotal connection 39 (Fig. 4) with a "lazy" bar or arm 40 secured to the outer end of a horizontal pin 41 which is journalled for free oscillation in another oil-tight bearing boss 42 (Fig. 10) on the front wall 2 of the base 1, axial movement of said pin being prevented by a thrust collar 43 at the inner end thereof. At its lower end, the overedge looper 36 (Fig. 4) has a pivotal connection 44 with an arm 45 at the outer end of a short horizontal oscillated shaft 46 which extends into the interior of the base 1 through another oil-tight bearing boss 47 on the front wall 2. As shown in Figs. 1 and 4, the opposing side edges of the web 7 and the throat plate 16 are complementarily notched to provide a clearance opening 48 in the extended free or over-hanging portion of the work support through which opening the swinging outer end of the overedge looper 36 passes from beneath to a point above the work support around the edge E of fabric F (Fig. 1) operated upon in the machine.

For the purpose of intermittently progressing the fabric F on the work support relative to the needle 32, we utilize in the present instance a main feeding element in the form of a four motion feed dog 50 and an auxiliary four-motion differential feed dog 51. The toothed portions of the feed dogs 50 and 51 operate upwardly through slots 52, in the throat plate 16, see Fig. 10, the differential dog operating in advance of the main dog to gather in the fabric to a predetermined extent (as desirable when knitted goods are worked in the machine to compensate for stretch) before it is presented to the needle 32. As shown in Figs. 8 and 10, the shanks of the feed dogs 50 and 51 extend horizontally inward into the base through a shallow opening jointly formed by a notch 53 in the top edge of the front wall 2, and the overlying plate section 9. Oppos-

ing the feed dogs 50 and 51 from above is a presser foot 55 which is pivotally connected intermediate its ends at 56 to a supporting shank member 57. As shown in Fig. 10, the shank member 57 is clamped at its upper end to the pendant portion of a stud 58 at the front end of a horizontal presser arm 59. At its rear end, the presser arm 59 is secured by a set screw 60 (Fig. 1) to one end of a transverse rock shaft 61 which is journalled in laterally-spaced bearing lugs 62 and 63 upstanding from the web 7. The presser foot 55 is yieldingly urged downwardly by a leaf spring 65 whereof one end is pierced to engage a vertical anchorage stud 66 in an upright boss 67 on the top of the web 7, and whereof the other end is bifurcated to similarly engage the upwardly-extending end of the stud 58 at the outer end of the presser arm 59. Regulation of the spring 65 is effected through a hook block 68 which empowers it at the center and which is adjustable up or down by means of thumb screw 69 whereof the shank threadedly engages downwardly into a boss on the top of the web 7. When desired or required to facilitate introduction or withdrawal 20 of the work beneath or from beneath the presser foot, the latter may be lifted through the medium of a control lever 70 (Figs. 1, 7 and 10) whereof the outer end is intended to be connected by a drop link with a knee press or foot treadle, these latter elements having been omitted from the drawings since they may be of any well known or approved construction. The lever 70 is freely fulcrumed on the end of the rock shaft 61 opposite that occupied by the presser arm 59, and is subject to a torsion spring 72 which tends to move it anti-clockwise in Fig. 7 so that it is normally maintained in engagement with an overhanging stop pin 73 in a post 74 rising from the web 7. As shown in Fig. 1, the spring 72 is coiled about 25 the fulcrum boss on the lever 70, one of its ends being secured to an anchorage screw 75 on the bearing lug 63 and its other end being hooked under said lever as at 76. Extending laterally from the fulcrum boss of the lever 70 is a lug 77 (Fig. 7), which, when said lever is depressed, engages a downward projection 78 on a collar 79 fixedly clamped to the end of the rock shaft 61 to turn the latter clockwise and thereby cause the presser arm 59 to be lifted for the purpose 30 previously mentioned. As shown in Fig. 7, a clearance ordinarily exists between the lug 77 and the projection 78 so that the presser foot 55 may rise and fall normally as required without interference by the control lever 70.

55 In certain instances of practice, it is desirable to trim the edge of the fabric before such edge is stitched. We have accordingly provided our improved sewing machine with a trimming means for the explanation of which reference will be 35 had now more especially to Figs. 1, 4, 7, and 10. As shown, this trimming means comprises a stationary ledger blade 80 which lies in a plane slightly to the right of the line of stitching A—A (Fig. 1), and which is pitched forwardly at an acute angle to the vertical in the direction of feeding. The ledger blade 80 is secured, with provision for endwise adjustment, in a suitable holder block 81 by a bolt 82, said holder block being shiftable transversely of a pendant lug 83 40 on the cover plate 9 for adjustment of the blade laterally of the stitching line A—A, and being fixable in shifted positions by a screw 84. The upper end of the ledger blade 80 extends into the clearance opening 48 in the work support of the 45 machine and terminates in a horizontal cutting

edge 85, as best shown in Fig. 10. Cooperative with the ledger blade 80 is a vertically-supported moving trimming blade 86 having a horizontal cutting edge 87 at its bottom end to shear against the cutting edge 85 of said ledger blade, and also a pendant tongue extension 88 by which the two blades are maintained in cutting alignment when in open position. At its upper end, the blade 87 is secured in a head 89 at one end of a horizontal rod 90 which is non-rotatable but axially slidably in laterally-spaced bearing bosses 91 and 92 at the front end of a horizontal supporting arm 93, see Fig. 1. As shown the arm 93 parallels the presser arm 59 and is freely fulcrumed on the rock shaft 61 in the interval between the bearing lugs 62 and 63. A coiled spring 95 in compression between the boss 92 and a collar 96 on the rod 90 yieldingly urges the latter leftward in Figs. 4 and 9 to maintain the moving blade 86 in shearing engagement with the ledger blade 80.

Suitable spring disk tensions 97, 98 and 99 (Fig. 1) are provided on the cover plate 10, respectively, for the needle and looper threads (not illustrated). En route from the tension 97 to the needle 32, the needle thread is passed through apertured pairs of opposing control fingers 100 and 101, respectively, mounted on the top of the web 7 and to the rear of the needle supporting arm.

The base 1 is utilized as a housing for actuating mechanism from which the various aforescribed externally-located moving parts of the machine derive their movements, said mechanism including a pair of transversely-extending parallel shafts 102 and 103 in the lower part of the base 1. As seen in Figs. 4 and 8, the shaft 102 extends outward through a bushed oil-tight bearing boss 105 on the right-hand side wall 5 of the base 1, and on its protruding end carries a combined hand and belt wheel 106 by which the machine may be driven either manually or under power. The other or left-hand end of the shaft 102 extends through a bushed bearing 107 on the partition 21 into the compartment or hollow of the offset 19 at the front of the base 1. Secured to the shaft 102 within the offset 19 is a balanced crank member 108 with a crank pin 109 to which is connected the lower end of a pitman 110 whereof the upper end is connected to a lateral stud 111 on the collar 28 previously referred to. By the means just described, the rotary motion of the shaft 102 is converted into endwise reciprocating movements of the bar 18 and the supporting needle 32. As shown in Fig. 4, oil is permitted to flow from the compartment 20 into the compartment 19 by way of a connecting duct 112 at the bottom of the partition 21. The moving parts within the compartment 19 are automatically lubricated by oil splash induced by intermittent dipping of a spoon 113 at the bottom end of the pitman into the oil supply. The companion shaft 103 is journalled adjacent its right-hand end in a bearing boss 114 upstanding from the bottom 6 of the base 1, while its left-hand end is rotatively supported in a bushed oil-tight bearing 115 on the left side wall 4 of said base. The shaft 103 is driven in unison with the shaft 102 but in the opposite direction through a pair of similar connecting intermeshing spur pinions 116 and 117. Mounted on the shaft 103 about midway between the gear 117 and the bearing 115 (Figs. 8 and 9) is a rotary eccentric actuator 118, which, through a vertical pitman 119 is coupled with a ball arm 120 on the inner end of the oscillating shaft 37 of the primary or under looper 35. Immediately to

the left of the rotary eccentric actuator 118 is another rotary actuator 121 which is in turn connected to a ball arm 122 at the inner end of the oscillating shaft 46 for the secondary or overedge looper 36 through a vertical pitman 123. Lift movements are induced in the feed dogs 50 and 51 through a vertical pitman 126, from a third rotary eccentric actuator 125 mounted on the shaft 103 immediately to the right of the bearing boss 115. At its upper end, the pitman 126 is connected to a headed screw stud 127 (Figs. 8 and 10) at the front end of the horizontal carrier bar 128 on which the main feed dog 50 is mounted, the rear end of said bar being pivotally connected at 129 to the upper end of a bifurcated upright rocker 130 on a horizontal rock shaft 131 within the base 1, at the rear and about midway of the height of the latter. The feed rock shaft 131 is journalled in three spaced bushed bearings 132, 133 and 134 (Fig. 8), the first of these being on the left-hand end wall 4 of the base 1, and the other two projecting forwardly from the rear wall 3. Horizontal to and fro or feed movements are imparted to the main feed dog 50 from a rotary actuator 135 on the right-hand end of the shaft 103 adjacent the bearing 114, see Figs. 7, 8 and 9. As shown, the rotary actuator 135 has a crank pin 136 which is adjustable by means of a screw 137 for the purpose of varying the feed stroke of the feed dogs 50, 51, the movements of said rotary actuator being converted into oscillatory movements of the feed rock shaft 131 as a consequence of the connection of the crank pin with a forwardly-extending arm 138 at the right-hand end of said shaft. The shank of the differential feed dog 51 (Fig. 10) is secured by a clamp screw 139 to one end of a horizontal rod 140 which is slidably endwise in spaced guide lugs 141 on the main feed bar 128. A collar 142 on the rod 140 in the interval between the guide lugs 141 has a lateral pivot stud 143 for connection of the forward end of a link 145. The other end of the link 145 is pivotally connected to a block 146 which is adjustable along an arcuate slot 147 in a lever plate 148 secured to one of the side arms of the feed rocker 130. Through this means, differential horizontal to and fro or feed movements are imparted to the differential feed dog 51. The coupling or coordination of the main and differential feed dogs in the manner just explained is well known and therefore, per se, forms no part of our invention.

The supporting arm 93 of the moving trimming blade 87 is vibrated up and down by a fifth rotary eccentric actuator 150 (Fig. 9) on the shaft 103 in the interval between the gear pinion 117 and the rotary actuator 118. Extending up from the rotary actuator 150 is a vertical pitman 151 which passes through an opening 152 in the web 7 and at its upper end is connected to a stud 153 projecting laterally from the cutter arm 93 at a point intermediate the ends of the latter. An oil seal is maintained at the orifice 152 by a group of washers 155 (Figs. 4 and 7) the uppermost one of which is caused to bear against a considerable margin around the orifice at the under side of the web under the influence of an upwardly-pressing finger spring 156, said washers having a snug sliding fit with the intermediate cylindric rod portion of the pitman 151.

For the most part, the moving elements within the chamber or hollow 20 of the base 1 are lubricated by splash oil dispersed by the gear pinions 116, 117 and by spoon projections 157, 158, 159 and 160 at the lower ends of the pitmans 119,

123, 26 and 51, which pinions and projections dip into the oil supply as clearly shown in Fig. 9. That portion of the oil thrown up by the gear pinions 116, 117 and impinging upon the under side of the cover plate 10 is directed by crossed fins 161 on said cover into an underlying reservoir 162 secured to the side wall 5 of the base by a screw 163. The oil collected in the reservoir 162 is conducted by means of tubes 165, 166 and 167, respectively, to the ball arms 120, 122 on the looper shafts 37, 46 and to the rotary actuator 135. A cylindrical block 168 of transparent material with a beveled bottom end face 169 extends down through an opening in the cover plate 10 to the bottom of the base 1 and serves as a direct-reading sight gauge by which the oil supply level may be checked from time to time. This oil gauge forms the subject of a co-pending application Serial No. 377,499 filed on May 27, 1940, by George Sauer.

The parts within the base 1 are accessible from above upon removal of the plates 9 and 10. An additional removable closure plate 170 over an opening in the side wall 5, (Figs. 8 and 9) makes possible access to the rotary actuator 135 for the purposes of ready inspection or adjustment. The parts within the offset 19 are in turn accessible by way of front and side openings covered by removable closure plates 171 and 172, see Figs. 2, 4, 6 and 10.

For the protection of the parts above the work support and to safeguard the operator from possible injury by contact with them, we have provided the machine with a comparatively shallow cover 175, see Figs. 1, 3, 5, and 10, which, at the center of its rear edge, is connected to the web 7 by a hinge 176 so that it may be swung upward and rearward when access to said parts is desired or required. At the center of its front edge, the cover 175 is fitted with a grasp knob 177, and also with a spring keeper 178 which is normally in yielding restraining engagement with a spring hold down catch 179. As shown in Figs. 3 and 5, ample clearance 180 is allowed beneath the left-hand side wall and beneath contiguous portions of the front and rear walls of the cover 175 to enable the operator to see the needle 32 and the presser foot 55 in guiding the right-hand edge of the fabric which is to be trimmed and over-edged, and to enable passage of the fabric rearward over the work supporting plate 9.

The operative cycle of the stitch-forming elements is shown in Figs. 11-16. In Fig. 11, the needle 32 has reached its lowermost position, while the under looper 35 is moving forward in readiness to take the needle thread loop (not shown) and the overedge looper 36 is still retreating. In Fig. 12 the under looper 35 is in the position of engaging the needle thread loop just as the needle 32 has begun to rise; while the overedge looper has reached the limit of its retractive stroke. In Fig. 13 the overedge looper 36 has passed beyond the path of the under looper 35 in readiness to carry its own thread loop (not shown) up and around the edge of the fabric, while the needle 32 continues in its ascent. In Fig. 14, the under looper 35 has started to retreat, the needle has reached the upper limit of its stroke, and the overedge looper 36 is moving upward and laterally into the path of the needle 32. In Fig. 15, the needle has begun its downward stroke and is in position to enter the thread loop (not shown) presented to it by the overedge looper 36. Fig. 16 shows the needle 32 continuing its

downward movement and is penetrating the fabric, the overedge looper 36 retreating, and the under looper advancing toward the needle.

Having thus described our invention, we claim:

5. In a sewing machine, a hollow box-like base containing a supply of lubricating oil and closed at the top; a flat horizontal work support associated with the base; an endwise-reciprocating needle bar extending up from within the base through an oil-tight bearing in the top of the base; a needle carried by the protruding end of the bar for movement on its work-penetrating stroke down through the work support; a looper to cooperate with the needle beneath the work support; actuating mechanism within the base from which the needle bar and the looper derive their movements in properly timed relation; and means for lubricating the actuating mechanism from the oil supply within the base.

20. A sewing machine according to claim 1, wherein the base is subdivided into two compartments, one into which the needle bar extends, and one in which the actuating mechanism is housed; and wherein an operating connection extends through a dividing wall from the actuating mechanism in the last mentioned compartment to needle bar operating mechanism in the first mentioned compartment.

25. In a sewing machine, a hollow box-like base containing a supply of lubricating oil and closed at the top; a flat horizontal work support associated with the base; an endwise-reciprocating needle bar extending up from within the base through an oil-tight bearing in the top of the base; a needle carried by the protruding end of the bar for movement on its work penetrating stroke down through the work support; a looper exteriorly of the base to cooperate with the needle in stitch formation beneath the work support; an operating shaft for the looper extending through an oil-tight bearing into the interior of the base; actuating mechanism within the base from which the needle bar and the looper operating shaft derive their movements in properly timed relation; and means for lubricating the mechanism from the oil supply within the base.

30. A sewing machine according to claim 1, wherein the actuating mechanism includes a pair of gear-connected shafts from one of which the needle operating mechanism is actuated, and from the other of which the looper is actuated; and wherein one of the gear-connected shafts extends to the exterior through an oil-tight bearing in the base and on its protruding end carries

35. A sewing machine according to claim 1, wherein the base is subdivided into two compartments, one into which the needle bar extends and one in which the actuating mechanism is housed; and wherein the actuating mechanism includes a pair of horizontal gear-connected shafts from one of which the looper is actuated, and the other of which extends through a dividing partition into the first mentioned compartment; a crank on the latter shaft within said first mentioned compartment; and a pitman connecting the crank with the needle bar.

40. A sewing machine according to claim 3, wherein the actuating mechanism includes a pair of inter-gear shafts from one of which the needle bar is actuated and from the other of which the looper is actuated; and further including a second looper exteriorly of the base to cooperate with the first looper and the needle

45. in the formation of overedge stitching; and a

separate shaft for oscillating the second looper also extending through an oil-tight bearing into the interior of the base for actuation with said first looper from the second of the two inter-gear shafts.

7. A sewing machine according to claim 3, wherein a portion of the work support extends beyond the base; wherein the needle passes through the extended portion of the work support; and wherein the looper cooperates with the needle beneath said extended portion of the work support.

8. A sewing machine according to claim 3, wherein a second looper exteriorly of the base cooperates with the first looper and the needle in the formation of overedge stitching; wherein a separate shaft for oscillating the second looper also extends through an oil-tight bearing into the interior of the base for actuation from the actuating mechanism; wherein a portion of the work support extends beyond the base; wherein the first looper coacts with the needle below the extended portion of the work support; and wherein the second looper in its movements passes through an opening in the extended portion of the work support from beneath the latter to a point above it and vice versa.

9. A sewing machine according to claim 3, wherein a portion of the work support extends beyond the base; wherein a feed element operates upwardly through an aperture in the overhanging portion of the work support; wherein operating connections for the feed element extend through a wall of the base to the interior for actuation from the actuating mechanism; and wherein a presser element cooperates with the feed element above the work support.

10. A sewing machine according to claim 3, wherein the actuating mechanism includes a pair of inter-gear horizontal shafts from one of which the needle bar is actuated, and from the other of which the looper is actuated; wherein a portion of the work support extends beyond the base; wherein a four-motion feed dog operates through a slot in the extended portion of the work support; wherein the feed and lift movements are imparted to the feed dog through connections interiorly of the base with the second mentioned shaft of the actuating mechanism; and wherein a presser foot reacts upon the feed dog from above the work support.

11. A sewing machine according to claim 3, wherein a portion of the work support extends beyond the base; wherein an intermittent feeding element operates at the overhanging portion of the work support to progress the work relative to the needle; and wherein a trimming means operates to trim the work in advance of the needle, said trimming means including a ledger blade secured within an opening in the extended portion of the work support, a coacting movable blade, a horizontal arm fulcrumed for up and down movement above the work support and carrying the movable blade, and an operating rod extending down through an oil-sealed opening in the base top from the arm to the interior of the base for actuation from the actuating mechanism.

12. A sewing machine according to claim 3, wherein a portion of the work support extends beyond the base; wherein an intermittent feeding element operates at the overhanging portion of the work support to progress the work relative to the needle; wherein the actuating mechanism includes a pair of inter-gear hori-

zontal shafts from one of which the needle bar is actuated, and from the other of which the looper is actuated; and wherein a trimming means operates to trim the work in advance of the needle, said trimming means including a ledger blade secured within an opening in the extended portion of the work support, a coacting movable blade, a horizontal arm fulcrumed for up and down movement above the work support and carrying the movable blade, and an operating rod extending down through an oil-sealed opening in the base top from the arm to the interior of the base for actuation from the second mentioned shaft of the actuating mechanism.

13. A sewing machine according to claim 3, wherein the actuating mechanism includes a pair of inter-gear horizontal shafts whereof one extends outward through an oil-tight bearing in a wall of the base and at the exterior carries a driving wheel; and further including a second looper exteriorly of the base to cooperate with the first looper and the needle in the formation of overedge stitching; a separate shaft for the overedge looper also extending through an oil-tight bearing into the interior of the base; a four-motion feed element which operates from beneath through an opening in the work support to intermittently advance the fabric relative to the needle; a work trimming means operative above the work support; an operating connection for the trimming means extending down through an oil-sealed opening in the base top; a rotary actuator whereby the needle bar is operated from one of the inter-gear shafts of the actuating mechanism; and a plurality of rotary actuators on the other of said inter-gear shafts for separately operating the looper shafts, for imparting feeding and lift movements to the feed element, and for imparting movement to the operating connection for the trimming means.

14. In a sewing machine, a hollow box-like base containing a supply of lubricating oil and closed at the top by a flat horizontal work support; an endwise reciprocating needle bar extending up from within the base through an oil-tight bearing in the work support; a needle carried by the bar above the work support; a looper to cooperate with the needle beneath the work support; a feed element operative upwardly through an opening in the work support; a presser foot to cooperate with the feed element from above the work support; work trimming means including a knife operative above the work support; an operating connection for the trimming knife extending down through an oil-sealed opening in the base top; actuating mechanism within the base from which the needle bar, the looper, the feed element and the trimming means all derive their movements in properly timed relation; means for lubricating the actuating mechanism from the oil supply within the base; and a retractable protective cover extending over the exposed portions of the needle bar, the presser means and the trimming means, said cover providing clearance beneath one of its side edges to permit traverse of the work support by the work and a clearance at the front to permit insertion of the work and to enable observation of the needle, the presser foot and the trimming knife.

15. In a sewing machine, a frame including a box-like base with a flat top closure whereof a portion serves as a work support; a reciprocating needle bar which extends upward through the top of the base and which at its protruding end carries a needle for movement down through the

work support; a complementary stitch forming instrumentality to cooperate with the needle beneath the work support exteriorly of the base; and mechanism within the base and below the plane of the work support for actuating said needle bar and complementary stitch forming instrumentality including a shaft which extends through an oil-tight bearing in a wall of the base to said instrumentality.

16. In a sewing machine a hollow box-like base with a flat top closure element whereof a portion serves as a work support; stitch forming mechanism including a needle bar which extends downwardly through oil tight bearing into the interior of the base, and which at its protruding end carries a needle for movement down through the work support, and a complementary stitch forming element to cooperate with the needle beneath the work support exteriorly of said base; and actuating means for the stitch forming mechanism including a shaft which is journaled in an oil-tight bearing in a wall of the frame.

17. In a sewing machine a hollow box-like base with a flat top closure element whereof a portion serves as a work support; stitch forming mechanism including a needle bar which extends downwardly through an oil tight bearing into the interior of the base and which at its protruding end carries a needle for movement down through the work support, and a complementary stitch forming element to cooperate with the needle beneath the work support exteriorly of said base; and actuating means for the stitch forming mechanism including a rotary shaft wholly within said base.

18. In a sewing machine a hollow box-like base with a flat top closure element whereof a portion serves as a work support; stitch forming mechanism including a needle bar which extends downwardly through an oil tight bearing into the interior of the base and which at its protruding end carries a needle for movement down through the work support, and a complementary stitch forming element to cooperate with the needle beneath the work support exteriorly of said base; and actuating means for the stitch forming mechanism including a pair of interconnected rotary shafts one of which is wholly within said base.

19. In a sewing machine, a closed hollow box-like base with a removable top closure means including a work support; stitch forming instrumentalities including a needle, and cooperating elements at opposite sides of said work support exteriorly of the base; actuating means within the base and operating connections extending up and laterally through oil-tight bearings in the top and in the wall structure of said base direct to said instrumentalities from the actuating means.

20. In a sewing machine, a closed hollow box-like base with a removable top closure means including a work support; stitch forming instrumentalities including a needle and cooperating elements at opposite sides of said work support exteriorly of the base; actuating mechanism within the base and beneath the work support including operating connections which extend up and laterally through oil-tight bearings in the top and sides of said base direct to said instrumentalities; and a supply of lubricating oil within the base from which the moving parts of the actuating mechanism are lubricated by splash action.

21. In a sewing machine, a closed hollow box-

like base with a top providing a work support; cooperating stitch forming instrumentalities above and below the work support exteriorly of the base; direct supporting and operating connections for said stitch forming instrumentalities extending outward through oil-tight bearings respectively provided in the top and in the side wall structure of said base; and actuating mechanism for said connections including a rotary shaft which is wholly disposed within the base.

22. In a sewing machine, a closed hollow box-like base with a top providing a work support; cooperating stitch forming instrumentalities above and below the work support exteriorly of said base; direct supporting and operating connections for said stitch forming instrumentalities extending outward through oil-tight bearings respectively provided in the top and in the side wall structure of said base; and actuating mechanism for said operating connections including a pair of shafts which are interconnected for synchronous rotation and whereof one is wholly contained within said base.

23. In a sewing machine, a frame with a hollow box-like base containing lubricating oil; a cover element which has an oil-tight perimetric seal with the top of the base and provides a work support; stitch forming, work feeding and trimming instrumentalities, the trimming instrumentalities comprising a stationary and a movable cutting blade exteriorly of the base above and below the work support; actuating mechanism within the base; operating connections extending through oil-tight bearings in the cover element and in the wall structure of the base from the actuating mechanism direct to the stitch forming instrumentalities; and a link which extends through an oil-sealed opening in the cover element of the base to the movable blade of the trimming instrumentalities.

24. In a sewing machine, a frame including a hollow box-like base which serves as an oil reservoir; a cover element sealed oil tight with the top of the base and providing a work support; stitch forming mechanism including a reciprocable needle and complementary stitch forming instrumentalities located respectively above and below the work support; feeding mechanism including a feed dog which operates through a slot in the work support; means contained within said hollow base for actuating the stitch forming and feeding mechanisms; and connections extending outward through oil-tight bearings in the cover element and in the side wall structure of the base for imparting movement to the complementary stitch forming instrumentalities.

25. In a sewing machine, a frame including a closed hollow box-like base with a top providing a work support; stitch forming mechanism including a reciprocating needle and complementary stitch forming instrumentalities positioned in operative relationship exteriorly of said base; direct operating means for said needle and said complementary stitch forming means beneath the work support including members which extend from above and from the side of the base through oil-tight bearings in its wall structure; and partitioning dividing the hollow of the base into two compartments in which the operating means for the needle and for the complementary stitch forming instrumentalities are respectively housed.
